UNITED STATES PATENT OFFICE.

GEORGE C. NAPHEYS, OF PHILADELPHIA, PENNSYLVANIA, ASSIGNOR TO
GEORGE C. NAPHEYS & SON, OF SAME PLACE.

DESIGN FOR A METAL PAIL OR CAN.

Specification forming part of Design No. 5,648, dated March 12, 1872.

Specification describing a Design for Metal Pail or Can, invented by GEORGE C. NAPHEYS, of the city of Philadelphia and State of Pennsylvania.

The nature of my design is fully represented in the accompanying photographic illustration, to which reference is made.

A is the body of the pail or can, which is of the form of the frustum of a spheroid, the sides of the vessel being slightly rounded from the bottom to the top. Around the vessel at each end there are ribs or beads, b, of the

character represented in the photographic illustration.

I do not claim, broadly, a ribbed or beaded pail or can of spheroidal shape.

What I claim as my invention is—

A design for a metal pail or can, as described and represented.

GEO. C. NAPHEYS.
